UNITED STATES PATENT OFFICE.

CHARLES A. BAILEY, OF CROMWELL, CONNECTICUT.

TOY PISTOL.

1,308,141.

Specification of Letters Patent.

Patented July 1, 1919.

Application filed December 30, 1918. Serial No. 263,837.

To all whom it may concern:

Be it known that I, CHARLES A. BAILEY, of Cromwell, in the county of Middlesex and State of Connecticut, have invented a new and Improved Toy Pistol, of which the following is a specification.

My invention relates to the class of toy pistols used for exploding the so-called paper caps, and an object of my invention, 10 among others, is to provide a pistol of this class that shall be extremely simple in its construction and one designed to create a pleasing impression upon the youthful mind.

15 A form of toy pistol embodying my invention and in the construction and use of which the objects herein set out, as well as others, may be attained is illustrated in the accompanying drawings in which—

20 Figure 1 is a view in side elevation of my improved toy pistol, the rearward position of the cap wheel and other parts being shown in dotted lines.

Fig. 2 is a view in elevation of that side 25 of the pistol opposite to that shown in Fig. 1.

In the accompanying drawings the numeral 3 indicates the handle of my improved pistol, 4 the barrel portion and 5 30 the body portion or frame, the whole being preferably composed of a single piece of metal formed to shape in any desired manner. The body portion may be flat upon one side (see Fig. 2) and may have a recess 35 6 on the opposite side formed by flanges 7, 8, extending in transverse directions, the flange 8 having an anvil 9 to receive blows delivered by a cap wheel 10.

This cap wheel has recesses 11 disposed at 40 intervals about its periphery, these recesses being formed to receive the anvil 9, as shown in Fig. 1 of the drawings. The cap wheel is mounted to rotate as well as to move back and forth from the anvil 9, 45 which movements may be obtained in various ways. In the construction herein shown a stud comprising the cap wheel pivot 12 projects into a slot 13 in the wall of the body or frame 5.

50 An actuating lever 14 is pivotally attached to the frame, the special form of attachment herein shown comprising a finger piece 15 extending from the upper end of the lever through a hole 16 in the frame, 55 as clearly shown in Fig. 2 of the drawings.

This lever is preferably in the form of a plate that serves to at least partially inclose the recesses 6, thereby forming a cap wheel chamber. Said lever has an extension 17, the end of which is bent over to form a lever 60 stop 18 positioned to strike a suitable stop located on the frame. The end of the actuating lever is formed into a trigger 20 shaped to receive a finger of the person operating the pistol, and a wheel actuating trip 65 21, comprising an integral prong projects inwardly from one edge of the lever in position to engage projections 22 at the ends thereof, which projections form the cap recesses 11. An inverted V-shaped spring 23 70 is secured at one end by a lip, the opposite end of the spring pressing against the cap wheel to force it against the anvil 9. The spring is held in place by friction against a lip 24 at the upper end of the handle and a lug 25 projecting from the upper edge of the frame, the spring being forced into place between these parts.

In operation of the pistol when the trigger is pulled backwardly the engagement of the 80 trip 21 with the projections 22 on the cap wheel moves said wheel away from the anvil 9 against pressure of the spring 23, the pivot of said wheel sliding in the slot 13. When the wheel has been moved backwardly 85 far enough to be free from the anvil the force applied by the trip of the wheel causes the latter to rotate on its pivot and locate the next succeeding recess 11 opposite the anvil. At this time the trip 21 and the 90 projection with which it is engaged are so relatively positioned that the trip slips from engagement with the projection and the spring throws the wheel with much force 95 against the anvil.

It do not contemplate that the noise created by my improved toy pistol shall be confined to that caused by an exploding cap, as the device may be arranged to create noises of various sorts, and the construction 100 of the cap wheel and other parts may be varied for such purpose. In fact the impact of the wheel against the anvil may be such as to create a sufficiently loud noise.

The structure of the frame herein shown 105 is highly satisfactory, but this may be changed to suit the fancy, and while I have shown in the drawings herein a preferred form of the device and described the principles of operation of my invention, I desire 110

to have it understood that the device shown is only illustrative, and that the invention may be carried out by other means.

I claim:

5. 1. In a toy pistol, a frame, a wheel mounted on the frame to slide substantially in a right line, a pivot on which said wheel rotates, means for guiding the wheel in its sliding movement, and means for operating the wheel.
10. 2. In a toy pistol, a frame, a wheel, a pivot for said wheel, said pivot being mounted to slide on the frame in a direction transverse to its axis, means on the frame to guide the pivot in its sliding movement, and means for operating the wheel.
15. 3. In a pistol, a frame having a recess in one side, a wheel mounted on the frame to slide thereon, a pivot on which said wheel rotates, means for guiding the wheel in its
20. 4. In a pistol, a frame having a recess in one side, a wheel mounted on the frame to slide thereon, a pivot on which said wheel rotates, means for guiding the wheel in its

sliding movement, and an actuating lever adapted to engage the wheel to operate it and to extend across said pivot and form a support for the wheel in its sliding movement.

25

4. In a toy pistol, a frame having a slot therein, a wheel having a pivot extending into said slot to permit rotating and sliding action of the wheel, and means for actuating the wheel to impart said sliding and 30 rotating action thereto.

5. In a toy pistol, a frame having a recess and a slot in one wall thereof, a wheel having a pivot extending into said slot to permit rotating and sliding action of the 35 wheel on the frame, a lever extending across said recess to support the wheel in its sliding and rotating actions, and means on the lever to engage the wheel to actuate it.

CHARLES A. BAILEY.
